REFRIGERATING SYSTEM

Franklin B. Hunt, Chicago, Ill., assignor to The
Liquid Carbonic Corporation, Chicago, Ill., a
corporation of Delaware

Application April 24, 1931, Serial No. 532,439

18 Claims. (Cl. 62—115)

The object of the present invention is to provide a refrigerating system particularly adapted for use where it is desired to maintain substantially a given temperature in one chamber and to maintain a materially lower temperature in another chamber, utilizing one compressor only in the system. The primary object of the invention is to provide a system of the character indicated in which the demands upon the refrigerating unit located in the first-mentioned chamber will necessarily be completely satisfied before any refrigerant is delivered to the unit in control of the second chamber. Further objects of the invention will appear as the description proceeds.

To the accomplishment of the above and related objects, my invention may be embodied in the forms illustrated in the accompanying drawing, attention being called to the fact, however, that the drawing is illustrative only; and that change may be made in the specific constructions illustrated and described, so long as the scope of the appended claims is not violated.

Fig. 1 is a diagrammatic representation of one embodiment of my invention; and

Fig. 2 is a diagrammatic representation of another embodiment of my invention.

The herein disclosed system is admirably adapted for soda fountain use, and I have illustrated a system specially designed for that use. It is to be understood, however, that the application of the system is not limited to soda fountains, but may be used elsewhere, and that it is not limited to any particular refrigerant, though it will be described as adjusted for use with sulfur dioxide.

Referring more particularly to Fig. 1, it will be seen that I have illustrated a compressor 10 driven by a motor 11 and adapted to supply compressed refrigerant through a cooling coil 12 to a condenser 13. The condenser 13 is connected by a pipe 14 to a refrigerating unit 15 running through the syrup enclosure and connected to one end 16 of a coil 17 located in the attemperating chamber for cooling soda and plain water. An automatic expansion valve 18 set, for instance, for a pressure of three and one-half pounds per square inch above atmospheric pressure is interposed in the line 14 in advance of the unit 15.

The opposite end 19 of the coil 17 is connected by a pipe 20 to an inlet port 21 located in the top of a trap 22.

The trap 22 comprises a casing providing a chamber 23 having an outlet 24 through its top, and having a second outlet 25 through its bot-

tom. A float 26 is positioned within the chamber 23 and may be provided with an arm 27 formed adjacent its upper end with an elongated slot 28. The slot 28 operatively receives a pin 29 carried by an arm 30 pivoted at 31 on a sleeve 32 carried by a conduit 34 communicating with the port 24. A valve 33 is carried by the arm 30 and controls flow through the conduit 34.

A pipe 35 connects the port 24 with a pipe 36 leading to the intake of the compressor 10, and preferably opening into the crank case of said compressor.

A pipe 37 connects the port 25 with one end 38 of a second refrigerating coil 39 located in a brine chamber for cooling ice cream. A second expansion valve 40, set for about ten pounds per square inch pressure absolute is interposed in the line 37 between the trap 22 and the coil 39. The opposite end 41 of the coil 39 is connected by the pipe 42 to the pipe 36.

A switch 44, controlled by a thermo-responsive element 45 disposed within the influence of the coil 39 controls current flow from the line 46 through the connections 47 to the motor 11.

If the whole installation is warm, liquid refrigerant will force its way through the line 14 past the valve 18 through the unit 15 and into the coil 17. At first, all of the refrigerant will be vaporized in the unit 15 and in the coil 17, so that only gaseous refrigerant will reach the trap 22. So long as there is no liquid in the trap 22, the weight of the float 26 will hold the valve 33 open and, with the compressor operating, all of such gaseous refrigerant will flow through the port 24 and the pipes 35 and 36 back to the compressor 10, no refrigerant being supplied to the coil 39.

Assuming that the units 15 and 17 are, in accordance with usual practice, submerged in water, ice will begin to form on those units. As this ice gets thicker and thicker, less and less of the refrigerant will be vaporized in these units, and liquid refrigerant will be fed into the trap 22. As the liquid level in the trap 22 builds up, the float 26 is elevated to move the valve 33 into position 45 to close the port 24. Flow of gas through the lines 35 and 36 is thus stopped, and flow of liquid to the coil 17 is likewise stopped. The compressor, however, continues to operate and reduce the pressure in coil 39 so as to allow flow of the liquid 50 from the trap 22 through the port 25 and line 37 and past the expansion valve 40, where the pressure is reduced to about ten pounds per square inch absolute. The refrigerant flows thence to the coil 39 to refrigerate the brine in which said 55

coil is submerged, and such refrigeration will continue as long as liquid flow from the trap 22 continues.

However, as soon as the liquid in the trap 22 has been exhausted sufficiently to permit the float 26 to drop, the valve 33 is opened and, because of the high pressure for which the valve 18 is set, the pressure in the coil 39 through the pipe 35 and pipe 42 closes the valve 40, so that no work will be done in the coil 39 until the valve 33 is again closed.

This shifting of flow from the coil 17 to the coil 39 continues until the brine around the coil 39 reaches a temperature at which the thermostatically operated switch 44 opens the motor circuit and stops the compressor.

It will be obvious that the compressor will continue to operate until sufficient liquid has vaporized in the coil 39 to bring the brine to the desired temperature. If the load on the coil 17 increases, as it does in practice, practically all of the liquid may vaporize in that coil, and very little, if any liquid will be fed to the coil 39 until the demands of this new load condition on the coil 17 have been satisfied.

Whenever the valve 33 is open, the crank case pressure of the compressor will rise to correspond to the setting of the valve 18. Thus, the high temperature load will be carried with a correspondingly high back pressure, giving high capacity and efficiency. The low temperature load, on the other hand, will be carried at a lower back pressure, but the liquid which reaches the expansion valve 40 has already passed through the valve 18 so that the flash gas which is evolved in cooling the liquid to the temperature impressed upon the coil 17 will go back to the compressor when the port 24 is open, at the high back pressure.

A refrigerant which carries oil with it will function in this system, as the oil is trapped in the trap 22, but will be discharged through the valve 40 and the coil 39, and returned to the crank case. This carrying of oil can not stop the compressor, since the oil, in passing through the coil 39, does not do any refrigerating work, and the machine must continue to operate until the thermostat 45 is satisfied.

Referring, now, to Fig. 2, it will be seen that I have illustrated a similar system so arranged as to obtain a multi-compression effect. The compressor 50 is provided with a crank shaft 51 within its crank case, said crank shaft being driven by a motor 82. A piston 52 connects a piston 53 to said crank shaft 51, the piston 53 being mounted for reciprocation in the cylinder 83 of the machine. The piston 53 is formed with a longitudinal bore 54 therethrough providing communication between the crank case and the cylinder, a check valve 55 being provided to enforce unidirectional flow through said bore 54 from the crank case to the cylinder.

Compressed refrigerant is supplied through a cooling coil 56 to a condenser 57, and thence by a pipe 58 through a refrigerating unit 59 connected to one end 60 of a coil 61, an expansion valve 62 being interposed in the line. The opposite end 63 of the coil 61 is connected by a pipe 64 to inlet port 66 of a trap 65 corresponding to the trap 22 and provided with a valved outlet port 67 and with a second outlet port 68. A line 69 is connected to the port 67, and delivers, at 70, into the cylinder 83 at a point just above the lower limit of the stroke of the piston 53. As is clearly illustrated, the port 70 is closed by the

piston at all times except when said piston is at the lower limit of its stroke.

A pipe 71 connects the port 68 with one end 72 of a second refrigerating coil 73, an expansion valve 74 being interposed in that line. The opposite end 75 of the coil 73 is connected by a pipe 76 with the crank case of the compressor 50. A thermostatic element 78 disposed within the influence of the coil 73 controls a switch 79 which in turn, controls the flow of current from a supply line 80 through the connections 81 to the motor 82.

The operation of the embodiment illustrated in Fig. 2 is substantially identical with the operation of the embodiment illustrated in Fig. 1, except that the high pressure returning gas flowing from the port 67 is injected directly into the cylinder of the compressor to increase the mass of gas therein just before the initiation of the up stroke of the piston 53.

I claim as my invention:

1. In a refrigerating system, a source of volatile liquid refrigerant, a refrigerating element connected to said source, a second refrigerating element connected to said source through said first refrigerating element, and automatic means for preventing flow of refrigerant to said second refrigerating element at all times when the demands upon said first refrigerating element are not satisfied.

2. In a refrigerating system, a source of volatile liquid refrigerant, a refrigerating element connected to said source, a second refrigerating element connected to said source through said first refrigerating element, valve means interposed between said refrigerating elements and normally preventing flow of refrigerant to said second refrigerating element, and means associated with said valve means, and actuatable only by liquid refrigerant discharged from said first refrigerating element and unresponsive to variation in pressure difference between said refrigerating elements to shift said valve means to permit flow of refrigerant to said second refrigerating element.

3. The combination with a compressor for volatile fluid and a condenser therefor, of a high-temperature cooling unit connected to said condenser and supplied therefrom, a trap having an inlet, a gas outlet, and a liquid outlet, means connecting said unit to said trap inlet, a low-temperature cooling unit, means connecting said low-temperature unit to said trap liquid outlet, a valve controlling said trap liquid outlet, a conduit connecting said gas outlet to the intake of said compressor, and a conduit connecting said low-temperature unit to the intake of said compressor.

4. The combination with a compressor for volatile fluid and a condenser therefor, of a high-temperature cooling unit connected to said condenser and supplied therefrom, a trap having an inlet, a gas outlet, and a liquid outlet, means connecting said unit to said trap inlet, a low-temperature cooling unit, means connecting said low-temperature unit to said trap liquid outlet, a valve controlling said trap liquid outlet, a float in said trap and operatively connected to said trap valve, a conduit connecting said gas outlet to the intake of said compressor, and a conduit connecting said low-temperature unit to the intake of said compressor.

5. The combination with a compressor for volatile fluid and a condenser therefor, of a high-temperature cooling unit connected to said condenser.

denser and supplied therefrom, an expansion valve interposed between said condenser and said unit, a trap having an inlet, a gas outlet, and a liquid outlet, means connecting said unit to said trap inlet, a low-temperature cooling unit, means connecting said low-temperature unit to said trap liquid outlet, an expansion valve interposed in said last-named connecting means, a valve controlling said gas outlet, a conduit connecting 5 said gas outlet to the intake of said compressor, and a conduit connecting said low-temperature unit to the intake of said compressor.

6. The combination with a compressor for volatile fluid and a condenser therefor, of a high-temperature cooling unit connected to said condenser and supplied therefrom, an expansion valve interposed between said condenser and said unit, a trap having an inlet, a gas outlet, and a liquid outlet, means connecting said unit to 15 said trap inlet, a low-temperature cooling unit, means connecting said low-temperature unit to said trap liquid outlet, an expansion valve interposed in said last-named connecting means and set to open at a pressure lower than the pressure required to open said first-named expansion valve, a valve controlling said gas outlet, a conduit connecting said gas outlet to the intake of said compressor, and a conduit connecting 20 said low-temperature unit to the intake of said compressor.

7. The combination with a compressor for volatile fluid and a condenser therefor, of a high-temperature cooling unit connected to said condenser and supplied therefrom, a trap having an inlet, 25 a gas outlet, and a liquid outlet, means connecting said unit to said trap inlet, a low-temperature cooling unit, means connecting said low-temperature unit to said trap liquid outlet, a valve controlling said gas outlet, a float in said trap and operatively connected to close said trap valve upon a rise of liquid in said trap, a conduit connecting said gas outlet to the intake of said compressor, and a conduit connecting said low-temperature unit to the intake of said compressor.

45 8. The combination with a compressor for volatile fluid and a condenser therefor, of a high-temperature cooling unit connected to said condenser and supplied therefrom, an expansion valve interposed between said condenser and said unit, a trap having an inlet, a gas outlet, and a liquid outlet, means connecting said unit to said trap inlet, a low-temperature cooling unit, means connecting said low-temperature unit to said trap liquid outlet, a second expansion valve interposed 50 in said last-named connecting means and set to open at a pressure lower than the pressure required to open said first-named expansion valve, a valve controlling said gas outlet, a float in said trap and operatively connected to said trap valve, said float being operable, upon collection of liquid refrigerant in said trap delivered through said high-temperature unit, to close said trap valve, a conduit connecting said gas outlet to the intake of said compressor, and a conduit connecting said 55 low-temperature unit to the intake of said compressor.

9. In combination, a compressor comprising a crank case, a cylinder, a crank shaft in said case, a piston operatively connected to said crank shaft and reciprocable in said cylinder, said piston being formed with a longitudinal bore, a check valve associated with said bore and enforcing unidirectional flow therethrough from said crank case to said cylinder, means for driving said crank shaft, 70 a condenser connected to the outlet of said com-

pressor, a high-temperature cooling unit having its one end connected to said condenser, a casing connected to the other end of said unit, said casing having a plurality of outlets, valve means controlling the course of fluid flow from said casing, means connecting one of said outlets to said cylinder at a point spaced outwardly beyond the inner limit of the stroke of said piston, means connecting another of said outlets to one end of a low-temperature cooling unit, and means connecting the other end of said last-named unit to 10 said crank case.

10. A refrigerating system comprising a compressor, a motor for driving said compressor, a refrigerating unit having its one end connected to the outlet of said compressor, a second refrigerating unit having its one end connected to the other end of said first refrigerating unit, and having its other end connected to the intake of said compressor, means interposed between said refrigerating units and operative to prevent fluid flow to said second refrigerating unit until the demands upon said first-mentioned refrigerating unit have been satisfied, means cooperating with said last-mentioned means for connecting the 25 last-mentioned end of said first-mentioned refrigerating unit to the intake of said compressor, and temperature-responsive means disposed within the influence of said second refrigerating unit for controlling operation of said motor.

30 11. In combination, a compressor for a volatile refrigerating fluid, a condenser connected to the outlet of said compressor, a motor for driving said compressor, a refrigerating coil having one end connected to said condenser to receive liquid refrigerant therefrom, an expansion valve interposed between said condenser and said coil, a trap having an inlet port and an outlet port adjacent its upper end and having an outlet port adjacent its lower end, a conduit connecting the 40 other end of said coil to said trap inlet port, a valve for controlling said upper outlet port, a float in said trap in control of said valve and operable to close said valve upon upward movement of said float, a conduit connecting said valved port to the intake of said compressor, a second refrigerating coil, a conduit connecting said lower outlet port to one end of said second coil, an expansion valve in said conduit, and a conduit connecting the other end of said second coil to 45 said compressor intake.

55 12. In combination, a compressor for a volatile refrigerating fluid, a condenser connected to the outlet of said compressor, a motor for driving said compressor, a refrigerating coil having one end connected to said condenser to receive liquid refrigerant therefrom, an expansion valve interposed between said condenser and said coil, a trap having an inlet port and an outlet port adjacent its upper end and having an outlet port 60 adjacent its lower end, a conduit connecting the other end of said coil to said trap inlet port, a valve for controlling said upper outlet port, a float in said trap in control of said valve and operable to close said valve upon upward movement of said float, a conduit connecting said valved port to the intake of said compressor, a second refrigerating coil, a conduit connecting said lower outlet port to one end of said second coil, an expansion valve in said conduit, a conduit connecting the other end of said second coil to 65 said compressor intake, and temperature-responsive means disposed within the influence of said second coil for controlling said motor.

70 13. In combination, a compressor for a volatile

- refrigerating fluid, a condenser connected to the outlet of said compressor, a motor for driving said compressor, a refrigerating coil having one end connected to said condenser to receive liquid refrigerant therefrom, an expansion valve interposed between said condenser and said coil, a trap having an inlet port and an outlet port adjacent its upper end and having an outlet port adjacent its lower end, a conduit connecting the other end 10 of said coil to said trap inlet port, a valve for controlling said upper outlet port, a float in said trap in control of said valve and operable to close said valve upon upward movement of said float, a conduit connecting said valved port to the intake 15 of said compressor, a second refrigerating coil, a conduit connecting said lower outlet port to one end of said second coil, an expansion valve in said conduit and set for a pressure lower than that for which said first-mentioned expansion 20 valve is set, and a conduit connecting the other end of said second coil to said compressor intake.
14. In combination, a compressor comprising a crank case, a cylinder, a crank shaft in said case, a piston operatively connected to said crank shaft 25 and reciprocable in said cylinder, said piston being formed with a longitudinal bore, a check valve associated with said bore and enforcing unidirectional flow therethrough from said crank case to said cylinder, a motor connected to drive said crank shaft, a condenser connected to the outlet of said compressor, a refrigerating coil having one end connected to said condenser to receive liquid refrigerant therefrom, an expansion valve interposed between said condenser and said 30 coil, a trap having an inlet port and an outlet port adjacent its upper end and having an outlet port adjacent its lower end, a conduit connecting the other end of said coil to said trap inlet port, a valve for controlling said upper outlet port, a 35 float in said trap in control of said valve and operable to close said valve upon upward movement of said float, a conduit connecting said valved port to said cylinder at a point spaced outwardly beyond the inner limit of the stroke of said piston, a second refrigerating coil, a conduit connecting said lower outlet port to one end of said second refrigerating coil, an expansion valve in said conduit, and a conduit connecting the other end of said second coil to said crank case.
15. In a refrigerating system, a source of volatile liquid refrigerant, a first refrigerating element, a second refrigerating element, means connecting said refrigerating elements in series with

said source, and means interposed between said refrigerating elements and operable to direct flow from said first refrigerating element to said second refrigerating element only after the demands upon said first refrigerating element have been 5 satisfied.

16. In a refrigerating system, a source of volatile liquid refrigerant, a refrigerating element connected to said source, a second refrigerating element connected to said source through said 10 first refrigerating element, and a diverter valve interposed between said refrigerating elements and operable to direct flow from said first refrigerating element to said source until the demands upon said first refrigerating element have been 15 satisfied, and thereafter to direct flow from said first refrigerating element to said second refrigerating element until the demands upon said first refrigerating element exceed the capacity of the refrigerant supplied thereto.

20

17. In a refrigerating system, a compressor for volatile liquid, a condenser connected to the discharge port of said compressor, a refrigerating element connected to be supplied with liquid refrigerant from said condenser, a second refrigerating element, a chamber having an inlet port, an upper outlet port, and a lower outlet port, means connecting said first refrigerating element with said inlet port, means connecting said upper outlet port with the intake port of said compressor, 30 means connecting said lower outlet port with said refrigerating element, a valve controlling said upper outlet port, and float means movable upwardly to close said valve.

25

18. In a refrigerating system, a compressor for volatile liquid, a condenser connected to the discharge port of said compressor, a refrigerating element connected to be supplied with liquid refrigerant from said condenser, a second refrigerating element, a chamber having an inlet port, an upper outlet port, and a lower outlet port, means connecting said first refrigerating element with said inlet port, means connecting said upper outlet port with the intake port of said compressor, 40 means connecting said lower outlet port with said second refrigerating element, a valve controlling one of said outlet ports, and float means completely dominating said valve and operable, only under the influence of liquid refrigerant supplied to said chamber, to shift said valve to permit flow 45 of refrigerant to said second refrigerating element.

FRANKLIN B. HUNT.
